UNITED STATES PATENT OFFICE.

WILLIAM J. CUMMINGS, OF JOLIET, ILLINOIS, ASSIGNOR TO SWEET, ORR & COMPANY, OF NEWBURGH, NEW YORK, A FIRM.

POCKET FOR GARMENTS.

No. 905,795.

Specification of Letters Patent.

Patented Dec. 1, 1908.

Application filed April 30, 1908. Serial No. 430,201.

To all whom it may concern:

Be it known that I, WILLIAM J. CUMMINGS, a citizen of the United States, residing at Joliet, in the county of Will and State of Illinois, have invented a certain new and useful Improvement in Pockets for Garments, of which the following is a full, clear, and exact description.

The object of this invention is to provide a combined safety watch and pencil pocket, from which the watch is not likely to escape accidentally by movement of the wearer, the watch-receiving portion being provided with a vent to render it practically self-cleaning.

The invention is designed for use primarily on the bibs of overalls, but it is applicable to coats and other garments.

The invention consists of a pocket closed entirely across its top save to leave a mouth for the pencil pocket when one is used, and having a vertically arranged flap-protected mouth, whose flaps so coöperate with the watch as to make it practically impossible for the watch to escape while the wearer changes the position of the body. In connection with such a pocket is a vent for the escape of any dirt entering the pocket.

In the accompanying drawings, illustrating the invention, in the several figures of which like parts are similarly designated, Figure 1 is a front elevation of a pair of overalls whose bib is supplied with the improvement. Fig. 2 is a perspective view of a fragment of the bib, on a larger scale, cut through the watch pocket mouth. Fig. 3 is a rear perspective view of a portion of the bib of Fig. 1 and showing in addition an inside pocket for a handkerchief. Fig. 4 is a perspective view of portion of a coat supplied with the improvement.

The overalls or coat may be of ordinary or any approved construction. As shown in Figs. 1, 2 and 3, the pocket is a patch-pocket, having a narrow piece 1 seamed in the central bib seam 2 and sewed down closed at top to the body material 3 of the bib, and hemmed and open at the bottom 4. This open bottom constitutes a vent through which dirt entering or gathering in the pocket may escape, thereby safe-guarding the watch from being scratched or otherwise injured. The other portion 5 of the pocket is sewed to the body fabric 3 at its top 6, side 7 and bottom 8, and if desired, the bottom of

the pocket may slant downwardly, as shown, toward the vent 4, to facilitate the automatic cleansing of the pocket. The edge 8 of the portion 5 is hemmed and stitched down to the portion 1 from the top edge to the point 9 and from the bottom edge to the point 10, thus leaving an opening between the points 9 and 10 which constitutes the mouth of the watch pocket. The adjacent edges of the pieces 1 and 5 overlap, as shown in Fig. 2, and these overlapping portions at the mouth constitute flaps which afford an additional safeguard against the escape of the watch as the wearer stoops over his work.

It will be understood that the meeting edges of the pieces 1 and 5 are stitched to each other as described, but they are not stitched to the body fabric 3, so that the inside pocket space extends both sides of these meeting edges. This is indicated in Figs. 1, 2 and 3, and especially by the lines of stitches in Fig. 3, and in this view the meeting edges and mouth are indicated by dash-and-dot lines, while the uniformly broken lines in that view indicate the lines of stitches which extend through the body fabric.

A portion of the pocket may be divided off by a line of through stitches 11 to form a pencil pocket 12 which has its mouth at the top.

As seen in Fig. 4, the invention may be applied to the breast of any ordinary coat, as a patch-pocket, but in this case both vertical sides will be sewed down to the body fabric alike. In all cases the mouth of the pocket will be hemmed in any suitable way.

As shown in Fig. 3, the bib may be provided with an inside pocket 13 to receive a handkerchief.

The parts are shown bulged out abnormally in Fig. 1 in order to better illustrate the construction. In practice, these parts will stretch out flat across the bib.

While I prefer to make the pocket a combination watch and pencil pocket, still it is within the invention to omit the pencil pocket feature, or to replace it with a receptacle for any other tool or instrument. The vent may be omitted also, if desired.

What I claim is.—

1. A patch-pocket for garments, having a portion secured to the body fabric at top and along one edge and free from attachment to such body fabric at its other edge, and another portion attached to the body fabric at

top, side and bottom and having its other edge lapped over the free edge of the first-mentioned portion and attached to said first-mentioned portion for a short distance from its top downwardly and for a portion of its length from the bottom upwardly, so as to leave an opening having overlapping loose flaps to constitute the mouth of the pocket.

2. A patch-pocket for garments, having a portion secured to the body fabric at top and along one edge and free from attachment to such body fabric at its other edge, and another portion attached to the body fabric at top, side and bottom and having its other edge lapped over the free edge of the first-mentioned portion and attached to said first-

mentioned portion for a short distance from its top downwardly and for a portion of its length from the bottom upwardly, so as to leave an opening having overlapping loose flaps to constitute the mouth of the pocket, the first-mentioned portion being hemmed and unattached to the body fabric at its bottom, so as to leave a vent at the lower corner only of the bottom of the pocket for cleaning the pocket.

In testimony whereof I have hereunto set my hand this 21st day of April, A. D. 1908.

WILLIAM J. CUMMINGS.
